JOHN P. REINECKE, OF PITTSBURG, PENNSYLVANIA, ASSIGNOR TO PITTSBURG WATER HEATER COMPANY, OF ALLEGHENY, PENNSYLVANIA, A CORPORATION OF NEW JERSEY.

BURNER.

976,294.

Specification of Letters Patent. Patented Nov. 22, 1910.

Application filed November 6, 1907. Serial No. 400,918.

To all whom it may concern:

Be it known that I, JOHN P. REINECKE, a citizen of the United States, residing at Pittsburgh, in the county of Allegheny and State of Pennsylvania, have invented certain new and useful Improvements in Burners, of which the following is a specification.

The invention relates to burners and particularly to the type that is employed in what are known as instantaneous water heaters. The invention has for its primary object; the provision of a burner which by slight alteration may be used either with a good quality of gas or a very poor quality. One embodiment of the invention is illustrated in the accompanying drawings, wherein:—

Figure 1 is a front elevation of a burner equipped with a wire screening member for use with a good quality of gas,

Figure 2 is a rear view partly broken away, and with the cap removed to show the screening wire,

Figure 3 is a longitudinal section through the burner of Figure 1,

Figure 4 is a rear elevation of a burner equipped with a grating, and

Figure 5 is a longitudinal section through the burner of Figure 4.

At the present time two general types of burners are employed, the first of which employs a fine screen and is designed for handling a good quality of gas, and the second is equipped with a grating for handling the gas and is adapted for use where a poor quality of gas is used. Due to a change of fuel or ignorance as to which form of burner is desirable, it is often necessary to change the burners from one type to the other after the burner is installed, and my new type of burner is designed to meet this condition and permit of a change from one type of burner to the other without the necessity of removing the burners from their mountings, and by merely changing the position of the body portion slightly and substituting one form of cap for another. The two sets of caps employed are furnished with the burner and the construction is such that it is a small matter to substitute one for the other when necessary.

The burner is shown as equipped with the screen in Figures 1, 2 and 3. Referring to these figures, 1 is the body portion which

is expanded at its lower and upper ends as indicated in Figure 1, 2 is the gas nipple upon which the body portion is mounted by means of the annular ring 3 integral with such body portion, 4 is the screen preferably of copper which fits over the obliquely opening upper end of the body portion, 5 is an upwardly and forwardly extending cap which clamps the edges of the screen to the body portion, and 6 are the bolts for securing the cap in position. Figures 4 and 5 illustrate the burner as supplied with the other form of cap and screening means. The cap in this instance consists of the casting 7, which is provided at its rear side with the horizontal slots 8, whereby the rear face of the cap constitutes a grating. The cap is held in position by means of the bolts 6 in precisely the same manner that the cap 5 is secured, and the openings for the bolts are so positioned that when the cap 5 is removed from the body portion 1, the cap 7 may be substituted therefor and secured by the same bolts. It will be noted that the burner when supplied with the cap 5 as indicated in Figure 3, will discharge to the front of the body portion, while this discharge will be to the rear of the body portion when such body portion is fitted with the cap 7 as indicated in Figure 5. In order that the position of the flame may not be disturbed when one form of cap is substituted for the other, the body portion 1 is mounted upon the gas nipple 2 in such manner that it may be adjusted about its axis, and in case the cap 5 is replaced by the cap 7, the body portion 1 is rotated 180° from the position of Figure 5. It will be apparent from the foregoing that a very small amount of labor is necessary to change the burners from one type to the other, and that all that is necessary to effect this transformation is the additional set of caps. It is obvious that various modifications in the shape of the caps employed, and the angles at which they are placed upon the body portion of the burner might be made without departing from the inventive idea involved. The screen 4 may be of any of the well known types having comparatively small openings, but preferably consists either of woven wire or perforated plate.

Having thus described my invention and illustrated its use, what I claim as new and

desire to secure by Letters Patent is the following:—

1. A burner comprising a body portion mounted for rotary adjustment about its axis and having a rearwardly opening top portion and a pair of screening constructions either of which may be applied to the opening, the one comprising a screen and a cap for directing the gas to the front of the body portion, and the other comprising a cap having a series of closely spaced slots there-through for directing the gas to the rear of the body portion.
2. In combination in a gas burner, an upper admission portion provided at its upper end with an expanded top portion open-

ing obliquely for directing the gas rearwardly, and a removable cap having oblique edges fitting the top portion, the discharge face of the said cap lying in substantially a vertical plane laterally opposite the oblique opening in the top portion and being provided with a plurality of closely spaced slots.

In testimony whereof I have hereunto signed my name in the presence of the two subscribed witnesses.

JNO. P. REINECKE.
